EYELASH-SIMULATING ROOTED FIBRE
 Charlotte Buettenback Johnson, Los Angeles, Calif., assignor to Mattel, Inc., Hawthorne, Calif., a corporation of California

Filed May 27, 1966, Ser. No. 553,469
 3 Claims. (Cl. 46—165)

ABSTRACT OF THE DISCLOSURE

Simulated eyelashes are provided on a doll having a rubber-like base simulating eyelids by embedding a plurality of strands of heat-settable plastic fibre in the base along the lower edges of the simulated eyelids, heat setting the fibre in an upwardly curved configuration and cutting the fibres to eyelash length.

Dolls traditionally have been fascinating playthings for children, especially little girls. Recent years have seen a particular phenomenon become existent in the toy industry. The teenage fashion doll has captured the imagination of the collective children's mind and has achieved a place therein virtually unequaled in doll history. The natural tendency of children, especially little girls, to play "grown up" has been captured and directed towards the teenage fashion doll. As a result, the industry has seen developed a family of teenage dolls characterized by a virtual living personality group and which have, if any single indicia can be used to categorize same, the characteristic of an existence in an adult world the child anticipates will be his or her own upon personal entrance into that adult world. The personalities created in the teenage doll field are de facto engaged in virtually every aspect of adult life that would be anticipated by a child of relative tender years. For example, dress, sport activity, family relationships, the boy-girl relationship incident to youthful development, as well as the myriad of day to day activities that characterize life in mid-twentieth century America re the natural habitat of the doll personalities. Though vicarious, their existence and activity are very real.

By the very mental intimacy of the association, the children, at play with their teenage dolls, experience a vista of human emotions normally associated with the entrance into an adult pattern of life. With typical childish enthusiasm and optimism, each child tends to live, through its teenage doll play activity, those desirable experiences which produce the maximum joy to the developing immature mind.

In duplicating or vicariously living adult activities with its teenage fashion doll, the child may pay particular attention to the doll's coiffure by either employing different wigs for different occasions or by dyeing the doll's hair. When the child's attention is centered on the doll's coiffure, the child naturally pays attention to the doll's eyelashes. In the past, simulated eyelashes have been painted around the eye openings of the teenage fashion doll. Simulated eyelashes of this type have the disadvantage that they detract from the realism of the doll's coiffure.

Specifically, then, the present invention comprehends a mode of providing eyelashes for a doll of the teenage fashion type which comprehends simulating curled eyelashes found in the adult world.

In view of the foregoing, it is the primary object of the present invention to provide a new and useful method of application of eyelash-simulating, rooted fibre to dolls.

It is another object of the present invention to provide a new and useful doll having hair-simulating, rooted eyelashes.

In accordance with the present invention, known meth-

2

ods of application of hair-simulating fibre to the scalp portion of a doll are used to sew a single row of fibres along the simulated eyelid of a doll. A single row of fibres may be attached to each simulated eyelid at the time the several rows of hair-simulating fibre are being sewn in rows along the top of the doll's head. The several rows of hair-simulating fibre on the doll's head may then be groomed into a suitable coiffure after which the fibres which simulate the eyelashes may be swept upwardly over the doll's forehead and secured in this position with a suitable net.

The fibres are then heat-set in this up-swept position. After the heat-setting operation, the eyelashes are trimmed to a suitable length, providing a short eyelash that is rather stiff and somewhat curled upwardly.

The features of the present invention which are believed to be novel are set forth with particularity in the appended claims. The present invention, both as to its organization and manner of operation, together with further objects and advantages thereof, may best be understood by reference to the following description, taken in connection with the accompanying drawings, in which like reference characters refer to like elements in the several views.

25 In the drawings:

FIGURE 1 is a perspective view of a doll's head having hair-simulating fibres attached to the skull and eyelid portions thereof;

FIGURE 2 is a cross-sectional view taken along line 30 2-2 of FIG. 1;

FIGURE 3 is a view similar to FIG. 1 except that the hair-simulating fibres on the scalp of the doll have been groomed and the hair-simulating fibres on the eyelids have been trained upwardly over the forehead of the doll;

35 FIGURE 4 is a side-elevational view of the structure shown in FIG. 3 with parts broken away to show internal construction;

FIGURE 5 is a view similar to FIG. 3 showing the appearance of the eyelashes after they have been heat-set and trimmed to a proper length; and

40 FIGURE 6 is a side-elevational view of the structure shown in FIG. 5 with parts broken away to show internal construction.

Referring again to the drawings, and particularly to FIGS. 1 and 2, a presently preferred embodiment of the invention is illustrated in connection with the production of a doll's head, generally indicated 10. The doll's head 10 may be formed of a resilient, rubber-like material, and may be molded, in a manner familiar to those skilled in the art, of a plastisol or other suitable plastic material.

45 The head 10 includes a scalp portion 12, a forehead 14, a pair of eyelids 16, 18, a nose 20, lips 22 and a chin 24.

A plurality of hair-simulating strands or fibres 26 and 50 28 may be applied to the scalp 12 and the eyelids 16 and 18, respectively, in accordance with a suitable process, such as that described in Seiderman Patent No. 2,636,460 for applying hair-simulating strands. Such a process, as applied to the present invention, includes the steps of vertically reciprocating the pointed end of a hollow needle, not shown, into, through and out of the rubber-like base forming the scalp 12 and the eyelids 16 and 18. The needle has an opening in the pointed end thereof and a strand of continuous fibre is threaded through the opening with the free end of the strand extending outwardly through the opening. The rubber-like plastisol has sufficient resiliency to grip the strand and maintain it in place so that the strand is repeatedly embedded in the base and formed into a plurality of loops 30 on the underside 32 of the scalp 12 and of a plurality of loops 34 on the inside 36 of the eyelid 16 and 18.

55 The strands 26 are then cut to a suitable length so

that they may be groomed into a coiffure 38, as shown in FIGS. 3-6. The strands 28 are left dangling down over the chin 24 of the doll 10 while the strands 26 are being groomed to form the coiffure 38. After this grooming step has been completed, however, the fibres 28 are trained upwardly over the forehead 14 and are maintained in place against the forehead 14 by placing a net-like band 40 around the head 10. The fibres 28 are then heat-set by bringing them to a temperature of from about 110° C. to about 116° C. The fibres 28 are then allowed to cool to room temperature after which the band 40 is removed and the fibres 28 are trimmed to a proper length for forming eyelashes 42, as shown in FIGS. 5 and 6. The heat sets the eyelashes 42 in an upwardly curved position given to them by pulling them up over the forehead 14.

The fibres 26 may comprise individual strands of a polyvinylidene chloride having approximately 360 denier per filament. The fibres 28 forming the eyelashes 42 may also comprise a polyvinylidene chloride, but these fibres have a much heavier body weight than the fibres 26, being approximately 30-120 denier per filament with 120 being preferred.

While the particular method of application of eyelash-simulating, rooted fibre herein shown and described in detail is fully capable of attaining the objects and providing the advantages hereinbefore stated, it is to be understood that it is merely illustrative of a presently preferred embodiment of the invention and that no limitations are intended to the details of construction, design or methods

steps herein shown and described than as defined in the appended claims.

What is claimed is:

1. In combination with a doll head having a forehead and a rubber-like base simulating eyelids, simulated eyelashes comprising:

a plurality of strands of fibre embedded in said base along the lower edges of said simulated eyelids, said strands comprising a heat-settable plastic material which has been heat-set in an upwardly curved configuration and cut to eyelash length.

2. A combination as stated in claim 1 wherein said strands comprise a polyvinylidene chloride having a denier of approximately 30-120 per filament.

3. A combination as stated in claim 1 wherein said doll head includes a rubber-like scalp portion having hair simulating strands of said fibre embedded therein, said strands being arranged in a coiffure.
